FRUIT GUARD

Albert A. Partner, Biglerville, Pa., assignor to
Rice, Trew & Rice Co., Inc., Biglerville, Pa., a
corporation of Pennsylvania

Application January 12, 1933, Serial No. 651,379

10 Claims. (Cl. 217—3)

This invention relates to a fruit guard and it is primarily an improvement on the guard as comprised in application Serial No. 637,814 filed October 11, 1932.

5 It is an object of the present invention to provide a guard which is intended to be disposed along a side edge of a box or kindred receptacle in which citrus fruit and the like is to be packed and wherein the guard is provided with means 10 to prevent rocking movement of the applied guard and more particularly in the event of separation between a side wall and the central wall or partition of the fruit box or container.

15 The invention consists in the details of construction and in the combination and arrangement of the several parts of my improved fruit guard whereby certain important advantages are attained and the device rendered simpler, less expensive and otherwise more convenient and 20 advantageous for use, as will be hereinafter more fully set forth.

The novel features of my invention will herein-after be definitely claimed.

25 In order that my invention may be the better understood, I will now proceed to describe the same with reference to the accompanying drawing, wherein:—

30 Figure 1 is a view in perspective illustrating edge guards constructed in accordance with an embodiment of my invention and in applied position;

Figure 2 is a fragmentary view partly in elevation and partly in longitudinal section through Figure 1;

35 Figure 3 is a view in plan of one of the guards as herein disclosed and unapplied.

As disclosed in the accompanying drawing, B denotes a box or kindred container having its central part intersected by a wall or partition 1. 40 Coacting with the box B in a conventional manner is a lid L.

A guard G embodying my invention is adapted to be disposed along each side of the box or container B, said guard being of a length to extend 45 from one end wall of the box to the other and to bridge the space between the applied lid and the associated side wall W of the box or container. The guard when so applied operates effectively to substantially eliminate liability of 50 injury to the fruit upon the application of the lid L and also avoiding the liability of some of the fruit falling out between the applied lid L and the upper margin of the associated side wall W.

55 My improved guard as herein disclosed com-

prises a band of relatively heavy paper stock, such as cardboard or other material capable of being used for the purpose desired. The band is preferably disposed on a curvature from one end to the other with the upper edge on an 60 outbow. The curvature of the outer edge is such as to approximately conform to the maximum bulge of the top layer of fruit packed within the box or container B thus assuring an effective bridging of the space between the applied lid L and a side wall W.

65 The guard or band G is also quite broad so that when it is in applied position it will extend a considerable distance within the upper portion of the box B so that the pressure from within of the box content or particularly an upper layer of fruit will coat with the lower marginal portion of the applied guard or band G to hold the same against the side wall W and thereby facilitate its maintenance in working 70 position.

75 The band or guard G when in its initially flat or blank form is provided in its central part and at substantially its transverse center with a longitudinally disposed slit a, the central portion of which having in communication therewith a transversely disposed slit b which opens at the inner or inbow edge of the guard or band G. Between this inbow or inner edge of the guard or band B and the ends of the slit a are 80 arranged the scored or otherwise weakened lines c herein disclosed as in parallelism with each other and with the slit b. The slits a and b together with the weakened lines c provide flaps 2 85 adapted to extend inwardly from the guard or band G for engagement with the opposite faces of the central wall or partition 1 when the guard or band G is in applied or working position. These flaps 2 when angularly disposed result in 90 the guard or band G being provided with a notch 95 3 of a width to readily receive the upper marginal portion of the outer wall or partition 1 of the box B.

95 While the flaps 2 can be folded inwardly of the band or guard G before applying such band or guard to a box, yet the desired angular arrangement of the flaps 2 may be effected at the time the guard or band G is being applied by bringing the portion of the guard or band between the weakened lines c into contact with 100 the upper portion of the central wall or partition 1. While the notch itself provides means to prevent the applied guard or band G from having rocking movement when the partition or wall 1 is within the notch yet it often occurs 105 110

that there is considerable separation between the side walls and central partition or wall of the box B due sometimes to the inward pressure of the box content, sometimes to the hasty and imperfect assembly of the box and for other reasons. Therefore, under such conditions should the guard or band G be disposed above or within such spacing the tendency of rocking movement of the guard or band G would be materially increased. However, this is avoided by the contact of the flaps 2 with the side faces of the central wall or partition 1, said flaps 2 being of a length sufficient to compensate for the general spacing just referred to between a side wall W and a partition or central wall 1 of the box. It is also believed to be clearly apparent that as a means to prevent rocking movement of the guard or band G, these flaps 2 in the event of the spacing conditions just mentioned also serve to materially facilitate the effective placement of the guard or band G in working position.

The extremities of the guard or band G are continued by end flaps 4 each of which being separated from the band or guard proper by a scored or other weakened line 5. As particularly illustrated in Figure 3, each of these lines 5 is on such an angle or bias with respect to the longitudinal axis of the band or guard G to assure close contact of the flap 4 from end to end with an end wall of the box as is clearly illustrated in Figures 1 and 2 of the drawing. These end flaps 4 particularly provide means for contact with the applied lid L to hold the applied guard against upward movement with respect to the box thereby further assuring effective maintenance of the guard or band in required working position.

From the foregoing description it is thought to be obvious that a fruit guard constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim.—

1. An edge guard for a fruit container comprising a band to be positioned along an upper edge of the container and extending above such edge, said band being of a length substantially equal to the distance between the ends of the container, said band intermediate its ends being provided with a longitudinally disposed slit and with a second slit substantially at right angles to the first named slit, said slits being initially in communication and opening at a margin of the band, said slits providing flaps to move outwardly with respect to the band to provide a notch to receive a wall of the container to hold the band in applied position, the flaps being laterally disposed with respect to the band for engagement with the opposed faces of said wall.

2. An edge guard for a fruit container comprising a band adapted to be positioned along an upper edge of the container and extending above such edge, said band being of a length substantially equal to the distance between the ends of the container, and the outer margin of

said band being curved on an outbow from substantially one end to the other, the central portion of the band having a notch intermediate the ends thereof to receive a part of the container to hold the band in applied position, and means on the band at opposite sides of the notch to engage said part of the container to hold the band against rocking movement.

3. An edge guard for a fruit container comprising a band adapted to be positioned along an upper edge of the container and extending above such edge, said band being of a length substantially equal to the distance between the ends of the container, and the outer margin of said band being curved on an outbow from substantially one end to the other, the central portion of the band having a notch intermediate the ends thereof to receive a part of the container to hold the band in applied position, and means on the band at opposite sides of the notch to engage said part of the container to hold the band against rocking movement, said means being disposed inwardly and laterally with respect to the band.

4. An edge guard for a fruit container comprising a band adapted to be positioned along an upper edge of the container and extending above such edge, said band being of a length substantially equal to the distance between the ends of the container, and the outer margin of said band being curved on an outbow from substantially one end to the other, the central portion of the band having a notch intermediate the ends thereof to receive a part of the container to hold the band in applied position, and means on the band at opposite sides of the notch to engage said part of the container to hold the band against rocking movement, said means being disposed inwardly and laterally with respect to the band.

5. A fruit guard comprising a band of paper-board having a side wall portion adapted to engage a side wall of a fruit box the full length thereof, and an end wall portion at each end of said side wall portion adapted to abut and engage the respective end walls, said side wall portion having a notch in the mid-section thereof which seats over the transverse center wall of the box, said guard having means at each side of the notch to engage the opposite faces of the center wall to hold the guard against rocking movement.

6. A fruit guard comprising a band of paper-board having a side wall portion adapted to engage a side wall of a fruit box the full length thereof, and an end wall portion at each end of said side wall portion adapted to abut and engage the respective end walls, said side wall portion having a notch in the mid-section thereof which seats over the transverse center wall of the box, and inwardly disposed flaps carried by the guard at opposite sides of the notch to engage opposite faces of the transverse wall to hold the guard against rocking movement.

7. An edge guard for a fruit container comprising a band adapted to be positioned along an upper edge of the container and extending above such edge, the central portion of the band having a notch intermediate the ends thereof to receive a part of the container to hold the band in applied position, and means on the band at opposite sides of the notch to engage said part of the container to hold the band against rocking movement.

8. An edge guard for a fruit container comprising a band adapted to be positioned along an

9. An edge guard for a fruit container comprising a band adapted to be positioned along an upper edge of the container and extending above such edge, the central portion of the band having a notch intermediate the ends thereof to receive a part of the container to hold the band in applied position, and means on the band at opposite sides of the notch to engage said part of the container to hold the band against rocking movement, said means being disposed inwardly and laterally with respect to the band.

10. An edge guard for a container comprising a band adapted to be positioned along an upper edge of a container and extending above said edge, the central portion of the band having means extending inwardly and laterally thereof and spaced apart a distance to frictionally engage the opposite faces of a wall of the container to hold the band in position when initially applied.
